UNITED STATES PATENT OFFICE.

THOMAS HENRY TEAL AND ROBERT ARTHUR CAMPBELL, OF JONESBOROUGH, TEXAS.

SASH-FASTENER.

SPECIFICATION forming part of Letters Patent No. 399,169, dated March 5, 1889.

Application filed December 27, 1888. Serial No. 294,737. (No model.)

To all whom it may concern:

Be it known that we, THOMAS HENRY TEAL and ROBERT ARTHUR CAMPBELL, citizens of the United States, residing at Jonesborough, 5 in the county of Coryell and State of Texas, have invented certain new and useful Improvements in Sash Holders and Locks Combined; and we do declare the following to be a full, clear, and exact description of the 10 invention, such as will enable others skilled in the art to which it appertains to make and use the same, reference being had to the accompanying drawings, and to the letters and figures of reference marked thereon, which 15 form a part of this specification.

Our invention has relation to sash holders and locks combined; and it consists in the novel construction and arrangement of its parts, hereinafter set out in this specification 20 and claim.

The object of this invention is to provide a cheap but serviceable window-sash holder and lock combined, which at the same time prevents rattling of the sash, which is so 25 troublesome and annoying in windy weather.

This invention is so constructed that it may be applied to all windows, whether in houses, cars, boats, or elsewhere, where the sash slides up and down.

In the accompanying drawings, Figure 1 is 30 a view showing the window-casing A and window-sash B with our invention attached thereto, part of the wood being cut away from both, whereby a sectional view of our invention is shown. Figs. 2, 3, 4, and 5 are detail views.

We cut a groove, c, in the face of the window-sash B, and a perforation, c', is cut from the face of said sash to its inner edge and 40 communicates with said groove, and a hole, c², which may be called the "spring-socket," is bored from the bottom of said groove into said sash large enough and deep enough to hold a spiral spring, D.

Our lock is described as follows: In said 45 spring-socket c² is a spiral spring, D, long enough for its inner end to rest on the bottom of said spring-socket and for its outer end to bear against the inner face of the casing A.

The lock-plate E is made long enough and

wide enough to fit in the groove c, and has a handle, e, which passes through the perforation c' to and a little beyond the inner edge of the window-sash, and is slightly turned up. This lock-plate is provided with a thimble, e', 55 which may be riveted, soldered, or otherwise secured to the same, or it may be cast with it, stamped, or otherwise formed. This thimble receives and covers the outer end of the spiral spring D, and the outer end of the said 60 thimble is by means of said spiral spring pressed against the inner face of the window-casing and keeps the sash from rattling, and in houses or other stationary structures will keep the sash from slipping down. This lock- 65 plate is provided at its lower end with hinge-nib e², which turns out and enters into a corresponding hole, f, in the covering-plate F. The covering-plate F is made a little longer and a little wider than the groove c, and is 70 countersunk in the face of the sash B, and completely covers the locking-bar E, except the thimble e', which passes through the opening f' in the said covering-plate.

In the face of the casing A is countersunk 75 a lock-plate, G, provided with an opening, g, large enough to receive the outer end of the thimble e'. We may put on one or as many of these locking-plates as we wish, or we may bore holes in their stead when putting on a 80 cheap lock. The hinge-nib e² on the lock-plate E, which works in the perforation f of the covering-plate F, acts as and answers the place of a hinge.

The operation of our lock is: Take hold of 85 the handle e and pull it inwardly until the outer end of the thimble e' is drawn back flush or less than flush with the outer face of the covering-plate F, and while holding it in this position raise or lower the window to the 90 position desired and then let the handle go, when the spring D throws the thimble through the opening f' and impinges it against the face of the casing.

When locking-plates G are used, the thimble 95 is made to enter the opening g in one of said plates.

Having described our invention, what we claim as new, and desire to secure by Letters Patent, is—

The combination, with a window-sash, of the spiral spring D, its inner end resting in the socket c^2 , its other in the thimble e' , locking-plate E, having the hinge-nib e^2 , working 5 in the perforation f , and thimble e' , receiving and covering the outer end of said spring, and handle e , said lock-plate and handle fitting and working in groove c , and perforation c' , covering-plate F, countersunk in the face of 10 said sash, covering said lock-plate, and pro-

vided with the perforation f' and opening f' , substantially as shown and described, and for the purposes set forth.

In testimony whereof we affix our signatures in presence of two witnesses.

THOMAS HENRY TEAL.

ROBT. ARTHUR CAMPBELL.
